Specification for Design.

Patented May 8, 1917.

Application filed March 17, 1916. Serial No. 84,978. Term of patent 7 years.

To all whom it may concern:

Be it known that I, HEBRON B. LAYMAN, a citizen of the United States, and residing in the city of New York, county and State of New York, have invented a new, original, and ornamental Design for a Connecting-Rod, of which the following is a specification, reference being had to the accompanying drawing, forming part thereof.

Figure 1 is a side view of a connecting rod showing my new design;

Fig. 2 a similar view at right angles to that of Fig. 1;

Fig. 3 a bottom plan view of the larger end of the rod; and,

Fig. 4 a cross section of the shank portion of the rod.

I claim:—

The ornamental design for a connecting rod as shown.

HEBRON B. LAYMAN.
